UNITED STATES PATENT OFFICE.

WILLIAM REHFUSS, OF LA CROSSE, WISCONSIN.

DOOR-LOCK.

1,161,972.

Specification of Letters Patent. Patented Nov. 30, 1915.

Application filed January 20, 1915. Serial No. 3,322.

To all whom it may concern:

Be it known that I, WILLIAM REHFUSS, a citizen of the United States, residing at La Crosse, in the county of La Crosse and State of Wisconsin, have invented certain new and useful Improvements in Door-Locks, of which the following is a specification, reference being had to the accompanying drawings.

10 This invention relates to door locks, and more particularly to locks of that character known in the art as panic locks, the purpose of which is to provide a lock for the doors of halls, theaters, or large auditoriums, 15 which may be easily and quickly operated by the application of pressure to release the doors for opening movement.

The invention has for one of its objects 20 to provide a lock of this character, the operating principle for which is applicable to either that type of door lock which cooperates with the keeper at the side edge of the door, or with a keeper located in the top of the door frame, the latter being commonly used in a double door construction.

It is a further object of the present invention to generally improve and simplify 25 the construction of locks of the above type and to produce such a device which consists 30 of very few parts all of simple form and, therefore, not liable to readily get out of order, the device as a whole, being capable 35 of manufacture at small cost.

With the above and other objects in view, 40 my invention consists in the novel features of construction, combination, and arrangement of parts to be hereinafter more fully described, claimed, and illustrated in the accompanying drawing, in which,

45 Figure 1 is an elevation showing my improved lock as applied to a single door, the locking bolt being horizontally movable for engagement in a suitable keeper on the door frame; Fig. 2 is a similar view showing the

45 lock employed for locking double doors at the top of the door frame; Fig. 3 is an enlarged elevation of the lock shown in Fig. 1, the lock case being in section, and certain 50 of the parts broken away; Fig. 4 is a detail perspective view of the rotatable sleeve of the locking bolt; Fig. 5 is a view similar to Fig. 3, of the locking device for double doors; and Fig. 6 is a section taken on the line 6—6 of Fig. 5.

55 Referring in detail to the drawing, and more particularly to Figs. 1, 3 and 4 there-

of, 5 designates the lock case, which is suitably secured to the inner face of the door adjacent its free edge. An operating rod 6, made up in sections suitably connected, has 60 angularly disposed end portions, one of which is journaled in a suitable bearing indicated at 7, also fixed upon the face of the door. The other end portion of this rod 6 is longitudinally extended through an opening in the inner end wall of the case 5, and terminates in a tubular guide or sleeve 8 for the locking bolt indicated at 9. This sleeve 8 is freely rotatable in the wall of the case 5, and adjacent to its inner end, said sleeve 70 is cut out or recessed on one side, as shown at 10. The edges of this recess taper inwardly or converge toward each other to the outer end of the recess, whereby the inclined cam walls 11 are formed. To the 75 shank of the locking bolt 9, a pin 12 is fixed, said pin being located within the recess or opening 10 of the sleeve 8. In the inner end of this sleeve 8, a coil spring indicated at 13, is arranged, and bears against the inner end 80 of the locking bolt. This spring normally acts to force the bolt outwardly through an opening provided in the outer end wall of the case 5 so that the end of the bolt will 85 properly engage in the keeper when the door is closed.

Normally, the intermediate portion of the rod or bar 6 is disposed in spaced relation to the face of the door. Assuming that a panic has occurred in a room or hall, the 90 door of which is provided with my improved lock, and the audience, in seeking an exit, crowd against the door, the body of a person striking the bar or rod 6, forces the same either upwardly or downwardly and 95 against the face of the door. A movement of this rod in either direction acts to rotate the tubular end or sleeve 8 thereof within the lock case, and one of the cam walls 11 of the opening or recess in said sleeve 100 bearing against the pin or stud 12 secured in the locking bolt, acts to force said bolt inwardly against the action of the spring 13 and thus retract the outer end of the bolt from engagement with the keeper 105 5 so that the door is permitted to swing open simply by pressure against the same. In this manner, it will be seen that there is no loss of time in opening the door, as the operation of the lock is practically automatic, and liability of serious injury or loss 110 of human life, to a great extent, minimized.

In Figs. 2, 5 and 6 of the drawing, I have shown a slightly different form of the lock, which is particularly designed for use upon double doors, where the locking bolt is vertically disposed for engagement in a keeper at the top of the door frame. The rod 6 is mounted in precisely the same manner as above described, and terminates in a horizontally disposed end portion rotatably mounted in the wall of the lock case 5 which is secured upon the face of the door at right angles to the position of the case shown in Fig. 1. The bolt 14 is vertically disposed and includes a shank section 15 which is threaded or otherwise detachably connected to a shank section within the case, and extends through suitable guides 16 secured in the door. The upper end of this section 15 is provided or formed with an enlarged head suitably fashioned for engagement in a keeper indicated at 17 secured in the top of the door frame. Upon the bolt 14, within the lock case, a plate or flange 18 of rectangular form in plan, is integrally formed and preferably provided with a curved or convex upper face. A coil spring 19 bears at one of its ends against this plate and at its other end against the bottom wall of the case and normally acts to force the locking bolt upwardly. A shoulder or lug 20 on the locking bolt, limits such movement thereof by engagement with the top wall of the case. The inner end of the rotatably mounted rod 6 terminates in a substantially semi-circular projection or extension 21, which is disposed immediately above the plate 18 at one side of the locking bolt. This form of the invention operates in precisely the same manner as above described or, in other words, when pressure is brought to bear against the rod 6 and the same is swung upwardly or downwardly, the extension 21 on the end of the rod, will bear at one of its ends upon the plate 18 on the locking bolt and force the same downwardly against the action of the spring 19, thus withdrawing the bolt from the keeper in the door frame. Thus, the doors may swing to open position by pressure against the same.

From the foregoing description, taken in connection with the accompanying drawing, it will be seen that I have produced a very serviceable and convenient panic lock which the ordinary person would have no difficulty in operating. The elements of the lock construction are extremely simple and liability of the same to get out of order is, therefore, obviated. By means of the lock, in case of panic in theaters, auditoriums and the like, created by an alarm of fire or other cause, congestion at the exits is immediately relieved by providing a free and unobstructed door opening through which a large number of persons may quickly pass. Thus, liability of injury to persons by being

knocked down and trampled under foot, is also avoided.

While I have shown and described the present preferred embodiments of my invention, it is, nevertheless, to be understood that the same is susceptible of other changes in the form, proportion, and arrangement of the several parts employed, and I, therefore, reserve the privilege of resorting to all such legitimate modifications as may be fairly embodied within the spirit and scope of the appended claims.

Having thus fully described my invention, what I desire to claim and secure by Letters Patent is:—

1. A panic lock including a slidably mounted spring pressed locking bolt provided with a bearing lug intermediate of its ends and a rotatably mounted operating member having a tubular end portion cut away on one side to accommodate said lug and providing a cam surface to co-operatively engage the lug when said member is rotated in either direction and retract the locking bolt.

2. A panic lock including a slidably mounted spring pressed locking bolt provided with a laterally projecting bearing lug intermediate of its ends and a rotatably mounted operating member having a tubular end portion cut away on one side to accommodate said bearing lug and providing cam means on the operating member co-operating with said bearing lug when said member is rotated, in either direction to retract the locking bolt.

3. A panic lock including a slidably mounted locking bolt, and a rotatable operating member axially aligned with the locking bolt and provided with cam means to co-act with means carried by the bolt whereby said bolt is retracted when the operating member is rotated in either direction.

4. A panic lock including a slidably mounted locking bolt provided with a bearing lug projecting from its periphery, and a rotatable operating member axially aligned with the locking bolt and provided with cam means to co-act with said lug when said member is rotated in either direction and retract the locking bolt.

5. A panic lock including a slidably mounted locking bolt provided with a bearing lug projecting from its periphery, and a rotatable operating member axially aligned with said bolt and having a sleeve in which the bolt is slidably engaged, said sleeve being provided with cam surfaces to co-act with said bearing lug when the operating member is rotated in either direction and retract the bolt.

6. A panic lock including a slidably mounted locking bolt provided with a bearing lug projecting from its periphery, and an operating member axially aligned with the

locking bolt and having a sleeve in which said bolt is slidably engaged, said sleeve being provided with an opening through which said lug projects, said sleeve at the edge of the opening having cam surfaces to co-act with the lug when said operating member is rotated in either direction and retract the bolt.

7. A panic lock including a slidably mounted locking bolt, and a rotatable operating member axially alined with said bolt and provided with a sleeve in which the bolt is slidably engaged, a spring housed within said sleeve and acting against the bolt to normally urge the same to its locking position, said sleeve being provided with cam means co-acting with means on the locking bolt to retract said bolt when the operating member is rotated in either direction.
- 10 8. A panic lock including a slidably

mounted locking bolt, and an operating member axially alined with said bolt and having a sleeve in which the bolt is slidably engaged, said sleeve being provided with a longitudinal opening and cam surfaces at one end of said opening, a bearing lug projecting from the periphery of the bolt, and a spring housed within said sleeve and acting against the bolt to normally urge the same to its locking position and hold the lug thereon in bearing contact with the cam surfaces of the sleeve whereby said bolt is retracted when the operating member is rotated in either direction.

In testimony whereof I hereunto affix my signature in the presence of two witnesses.
